UNITED STATES PATENT OFFICE.

THOMAS M. KEMPER, OF CRECY, TEXAS.

DESIGN FOR A PICTURE FRAME.

Application filed March 8, 1923. Serial No. 5,409. Term of patent 3½ years.

To all whom it may concern:

Be it known that THOMAS M. KEMPER, a citizen of the United States, residing at Crecy, in the county of Trinity and State of Texas, has invented a new, original, and ornamental Design for Picture Frames, of which the following is a specification, reference being had to the accompanying drawing, forming part thereof.

The figure is a perspective of a picture frame showing my new design.

I claim:

The ornamental design for a picture frame, as shown.

THOMAS M. KEMPER.
